FRANK XAVIER SMUCK, OF KITCHENER, ONTARIO, CANADA.

ROWING DEVICE.

1,313,130.

Specification of Letters Patent.

Patented Aug. 12, 1919.

Application filed March 7, 1919. Serial No. 281,252.

To all whom it may concern:

Be it known that I, FRANK XAVIER SMUCK, of the city of Kitchener, in the county of Waterloo, in the Province of Ontario, Canada, have invented certain new and useful Improvements in Rowing Devices, of which the following is the specification.

My invention relates to improvements in 10 rowing devices and the object of the invention is to devise a rowing device which will propel the boat in the direction which the rower is facing and at the same time to provide means whereby the rowlock may be 15 raised or lowered to correspond with the depth of the boat in the water and also to provide means whereby my device may be readily attached to or detached from the side of the boat and it consists essentially 20 of the following arrangement and construction of parts as hereinafter more particularly explained.

Figure 1 is a perspective view of my device.

Fig. 2, is an enlarged sectional view taken 25 through my device in proximity to the gunwale of the boat.

In the drawings like characters of reference indicate corresponding parts in the 30 various figures.

1 indicates the gunwale of a boat. 2 indicates a bar which is designed to rest upon the upper edge of the gunwale and to form the main support for my device.

35 In order to secure the bar 2 to the gunwale I provide swinging links 2^x located at each end of the bar 2 and pivoted to the gunwale, the links when in the vertical position, surrounding the bar 2.

40 3 indicates an eccentric locking lever swung upon each link 2^x and adapted, when swung inwardly, to clamp the bar 2 against the upper edge of the gunwale. 4 indicates standard bars extending horizontally from 45 the bar 2 and outwardly from the boat. 5 indicates a frame which is swung at 5^x between the standards 4, the inner end of the frame next to the boat being held in position by a locking pin 5° extending through an

50 orifice 4^x formed in one of the standards 4 and into an orifice 5° formed in one of the side bars of the frame 5 and adapted to be brought into alignment with the orifice 4^x.

In order that the frame may be adjusted 55 to any desired angle I have provided an upwardly extending lug 5° extending upwardly

from the side bar of the frame 5 having perforations 5° formed therein in vertical alignment with the orifice 5°.

6 indicates a U-shaped bracket secured to 60 the front portion of the frame 5, such bracket forming the rowlock through which the oar 7 passes freely, the oar being held in position within the rowlock by a cross pin 7^x extending through a perforation 6^x in the 65 side portion of the bracket 6. The shank 7^x of the oar 7 intermediately of its length is provided with a ball member 7° and at its extreme inner end with a longitudinally extending pin 7° on which is mounted a roller 7° 75. 8 indicates an oar handle which is pivoted intermediately of its length upon the bar 2 at 8^x. The outer end of the handle is provided with opposing socket nuts 8^x extending to each side of the ball 7° so that the 80 ball fits therebetween. It will be seen that when the outer end of the handle 8 is swung in one direction, for instance, in the direction of arrow that the outer end of the oar 7 will be swung in the same direction propelling the boat in the direction of arrow A 85 or in the direction which the operator holding the oar handle 8 faces. 9 indicates a cam piece which is secured to the outer face of the inner bar 5°. The ends of the cam 90 piece 9 are tapered off at 9^x and 9° forming lower curved faces 9° and 9° and upper curved faces 9° and 9° forming the ends of the cam piece into a sharp edge which extends in a slightly converging direction as 95 will be clearly seen on referring to Fig. 2.

10 indicates a downwardly curved finger extending from the side bar 5° of the frame 5 and in proximity to the curved portion 9° of the cam 9, it being sufficiently far away 95 from such curved portion to allow of the passage of the roller 7°.

11 indicates an upwardly curved finger carried by the frame 5 and located opposite the end 9° of the cam piece 9, the space between the finger and the end of the cam piece being sufficient to allow of the passage of the roller 7°. 12 indicates a strap which is secured to each side bar of the frame 5 extending across the frame over the inner end of 105 the oar member 7 at a point adjacent to the roller 7° and cam piece 9. The fingers 10 and 11 may be spring fingers.

Having described the principal parts involved in my invention I will briefly describe the operation of the same.

As the oarsman pulls the oar handle 8 in

the direction of arrow the oar handle swings upon the bolt 8^x which forms the fulcrum thereof. The opposite end of the oar handle 8 therefore swings in the opposite direction 5 to arrow carrying the ball 7' attached to the shank of the oar member in a corresponding direction, swinging the oar member 7 in the rowlock 6 and carrying the roller 7^z over the upper surface of the cam piece 9 until it 10 strikes the upwardly curved finger 11 which directs it down the curved upper portion 9^z of the cam piece 9, this taking place at the end of the stroke of the oarsman. By the return stroke the roller is carried against the 15 curved lower face 9^z of the cam piece 9 and is thereby directed rearwardly with the blade of the oar clear of the water, this movement continuing until the curve 9^z directs the roller 7^z upward against the finger 10, which guides the roller up to a position over the cam piece 9. The operation is then repeated.

It may be found necessary to adjust the blade of the oar according to the depth of 25 the boat in the water in order that the oar may clear the water on its return stroke. For this purpose I have provided the frame 5 swingably mounted in the standard members 4. When it is desired to adjust the 30 frame the pin 4^x is withdrawn from the orifice 5' and the inner end of the frame forced down until one of the holes 5^z is brought into alignment with the orifice 5^z when the pin 4^x is slipped back into place thereby 35 holding the frame 5 at a slightly downwardly inclined angle toward the side of the boat, and thereby raising the outer end or blade of the oar to a higher level so that as it swings in the rowlock it will clear the water 40 on its return movement.

If it is desired to use the boat as an ordinary boat, that is, to use the ordinary oars all that it is necessary to do is to swing the cam levers 3 outward so as to free the links 45 2^x. The links 2^x may be then swung outward clear of the bar 2. The bar 2 and frame 5 and the oar members carried thereby may be then removed and the usual rowlock placed in position in the gunwale of 50 the boat and the ordinary oars used.

From this description it will be seen that I have devised a very simple device whereby a boat may be propelled in the direction the occupant of the boat is facing and at the 55 same time provided simple means whereby the point of swing of the oar formed by the rowlock may be adjusted vertically in order to give the blade of the oar greater clearance on its return stroke.

60 What I claim as my invention is:

1. A rowing device comprising a frame adapted to be carried by the gunwale of the boat, a divided oar, one member comprising a blade and a shank portion and the other 65 member a handle portion and shank por-

tion overlying the aforesaid shank portion, a rowlock carried by the outer portion of the frame in which the shank portion of the oar blade bears, a pivotal connection between the handle portion of the oar and the inner 70 portion of the frame, a ball and socket connection between the outer end of the shank portion of the handle and the intermediate portion of the shank of the blade, and means for guiding the inner end of the shank of 75 the blade so that the blade passes rearwardly through the water by the rearward stroke of the handle and forwardly clear of the water by the forward stroke of the handle.

2. A rowing device comprising a frame 80 adapted to be carried by the gunwale of the boat, a divided oar, one member comprising a blade and a shank portion and the other member a handle portion and shank portion overlying the aforesaid shank portion, a 85 rowlock carried by the outer portion of the frame in which the shank portion of the oar blade bears, a pivotal connection between the handle portion of the oar and the inner portion of the frame, a ball and socket 90 connection between the outer end of the shank portion of the handle and the intermediate portion of the shank of the blade, means for guiding the inner end of the shank of the blade so that the blade passes 95 rearwardly through the water by the rearward stroke of the handle and forwardly clear of the water by the forward stroke of the handle, and means for detachably connecting the frame to the gunwale of the boat. 100

3. A rowing device comprising a frame adapted to be carried by the gunwale of the boat, a divided oar, one member comprising a blade and a shank portion and the other member a handle portion and shank portion overlying the aforesaid shank portion, a rowlock carried by the outer portion of the frame in which the shank portion of the oar blade bears, a pivotal connection between the handle portion of the oar and the inner portion of the frame, a ball and socket connection between the outer end of the shank portion of the handle and the intermediate portion of the shank of the blade, a cam member comprising a bar having tapered ends secured to the inner portion of the frame, a cam roller carried by the inner end of the shank of the oar blade adapted to engage the upper and lower faces of the cam member, and means for guiding the 110 roller therearound as the oar handle is reciprocated. 115

4. A rowing device comprising a frame adapted to be carried by the gunwale of the boat, a divided oar, one member comprising 125 a blade and a shank portion and the other member a handle portion and shank portion overlying the aforesaid shank portion, a rowlock carried by the outer portion of the frame in which the shank portion of the 130

- oar blade bears, a pivotal connection between the handle portion of the oar and the inner portion of the frame, a ball and socket connection between the outer end of the shank 5 portion of the handle and the intermediate portion of the shank of the blade, a cam member comprising a bar having tapered ends secured to the inner portion of the frame, a cam roller carried by the inner end 10 of the shank of the oar blade adapted to engage the upper and lower faces of the cam member, an upwardly curved finger carried by the frame at one end of the cam piece and a downwardly curved finger carried 15 by the frame at the opposite end of the cam piece, and a strap member extending across the frame over the shank of the oar handle in proximity to the cam roller when the cam roller is in contact with the upper face of the 20 cam piece.
5. A rowing device comprising a supporting frame adapted to be carried by the gunwale of a boat, a swinging frame carried in the supporting frame, means for adjustably 25 securing the inner portion of the frame in position, a rowlock carried by the outer portion of the frame, an oar handle pivotally secured intermediately of its length to the inner portion of the supporting frame, an 30 oar member comprising a blade and shank held within the rowlock, a ball and socket connection between the outer end of the oar handle and the intermediate portion of the shank of the oar blade, and means for sup- 35 porting the inner end of the shank of the

oar blade as it travels on its forward stroke and for guiding it on its return stroke so as to carry the blade of the oar clear of the water.

6. A rowing device comprising a frame 40 having a bar having ends projecting beyond the frame and adapted to rest upon the gunwale of the boat, a divided oar, one member comprising a blade and a shank portion and the other member a handle portion 45 and a shank portion overlying the aforesaid shank portion, a rowlock carried by the outer portion of the frame in which the shank portion of the oar blade bears, a pivotal connection between the handle portion 50 of the oar and the inner portion of the frame, a ball and socket connection between the outer end of the shank portion of the handle and the intermediate portion of the shank of the blade, means for guiding the 55 inner end of the shank of the blade so that the blade passes rearwardly through the water by the rearward stroke of the handle and forwardly clear of the water while the forward stroke of the handle loop members swung in the gunwale and adapted to extend over the projecting ends of the bar, and eccentric levers swung upon the upper portion of each loop and adapted to bear against the upper face of the project- 60 ing portion of the bar.
